SEALING PAD FOR RAILROAD TIES

Jacob Rush Snyder, Cleveland, Ohio

Application August 12, 1952, Serial No. 303,860

4 Claims. (Cl. 238—283)

This invention relates to deformable hollow pads or capsules adapted to be positioned between a railroad tie and a tie plate for increasing the useful life of the railroad tie. Specifically, this invention relates to a hollow deformable sealing pad which contains a mobile material capable of flowing in the pad for causing the pad to accommodate itself to the shape of surrounding surfaces and form bead-like seals which prevent entrance of moisture, sand, or other extraneous material between two pressed-together surfaces such as between a metal railroad tie plate and its wooden supporting tie.

The commercial life of wooden railroad ties is frequently shortened by moisture accumulation under the tie plate, which causes wood fiber softening and decay in the tie, and by the grinding action of sand and grit-like particles creeping in between the plate and the tie. Due to vibration in the rails and tie plate this extraneous matter will form a good grinding compound which rapidly wears away the wood tie and causes a deeper seating of the tie plates. Further, since the ties are surface treated and since the conventional scarfing of the tie to receive the plate removes the heavy protective coating on the outer surface of the tie, it is doubly important that the scarfed surface be sealed from moisture, which will induce decay.

Prior known railroad tie pads have been of the cushion type. The tie pad of the present invention, however, is not a cushion but is in the nature of a deformable capsule or envelope carrying a fluid which will flow to all low pressure areas for bulging or otherwise deforming the envelope or capsule material into sealed relationship with surrounding parts. The plurality of seals created by deformation of the envelope or capsule effectively prevents entrance of all extraneous matter and moisture between the tie plate and the tie.

The pads of this invention are formed from tough, impervious sheet material and a fluid that will flow at all temperatures encountered by railroad ties. Preferred sheet material for forming the container or skin of the pad are tough, pliable resins which are not affected by the preservative material in the railroad tie or by the fluid material therein. These resins should remain pliable at all temperatures of operation and include resins such as polyethylene, polystyrene, polyamides, polyvinyls and the like. An added desirable property is heat-sealability of the resins for ease in closing the envelope or capsule.

The fluid in the pad should flow at all temperatures of operation, should not have a high vapor pressure at elevated temperatures of operation and should not be destructive to either the tie plate or the tie in case of leakage from the envelope. Suitable materials are unctuous flowable grease-like masses composed of hydrocarbon greases, asphalt, creosote, and flowable tars and pitches.

It is then an object of this invention to provide a railroad tie pad which will seal the confronting surfaces of a tie plate and a tie to prevent deterioration of such surfaces.

2

A further object of this invention is to provide a fluid-filled railroad tie pad.

Another object of this invention is to provide a railroad tie pad composed of an impervious envelope or capsule containing a sealed-in flowable fluid capable of deforming the envelope or capsule into sealed confronting relation with a railroad tie and a tie plate.

A specific object of the invention is to provide a sealing pad for railroad ties which will form a marginal bulge around the railroad tie plate to form a seal that will prevent ingress of moisture and dirt between the tie plate and tie.

A still further object of the invention is to provide a sealed fluid-containing tie pad for railroads wherein the skin of the pad is deformed by the fluid into full conforming relationship with opposed tie plate and railroad tie surfaces without being punctured.

Another object of this invention is to provide a railroad tie pad of slightly larger dimensions than a tie plate to be used in conjunction therewith so that the pad will provide a sealing bead around the periphery of the tie plate.

Other and further objects of this invention will be apparent to those skilled in the art from the following detailed description of the annexed sheet of drawings, which, by way of preferred examples only illustrate two embodiments of the invention.

On the drawings:

Figure 1 is a plan view of the railroad tie pad according to this invention.

Figure 2 is a longitudinal cross-sectional view of the pad of Figure 1 taken along the line II—II of Figure 1.

Figure 3 is a plan view, with parts in horizontal cross-section, of an assembly of railroad track, tie plate, railroad tie and spikes, including the pad of this invention between the tie plate and the tie.

Figure 4 is a vertical cross-sectional view of the assembly of Figure 3 taken along the line IV—IV of Figure 3.

Figure 5 is a fragmentary vertical cross-sectional view taken along the line V—V of Figure 3 and showing the condition of the pad before the spike is inserted.

Figure 6 is a plan view similar to Figure 1 illustrating a modified embodiment of the pad.

As shown on the drawings:

In Figures 1 and 2 the reference numeral 10 designates generally one form of railroad tie pad according to this invention. The pad 10 is composed of a flat tube 11 of heat-sealable, impervious, tough plastic material such as polyethylene. The tube 11 provides a top face 11a and a bottom face 11b. The two faces are joined at their ends by heat-sealed margins 12, and, of course, have integral side edges. A closed envelope or capsule is thereby provided. Prior to completely heat-sealing the envelope 11, there is introduced between the faces 11a and 11b, a fluid material which is inert to the polyethylene envelope, and which will remain liquid or flowable at all temperatures encountered in connection with railroad use of the pad. This material is identified at 13 and separates the faces 11a and 11b except at portions where they are heat-sealed together as at the margins 12, the solid spots 14, and the perforated spots 15. These spots 14 and 15 are positioned to register with spike holes in the tie plate under which the pad is to be mounted. The spots 14 and 15 are created by heat-sealing to unite the top and bottom faces 11a and 11b of the tube or envelope at the designated area. The spots 14 are imperforate but the spots 15 have central apertures 15a to receive the spikes.

Spikes are always used through the apertures 15a but the spots 14 are not apertured because spikes are not always used in addition to the spikes which are used

at the spots 15. The fluid 13 as explained above, may be tar, grease, creosote, or the like material, in proper blended relation so that it remains fluid at all operating temperatures. The fluid 13 is used in just sufficient quantities so as to separate the faces 11a and 11b at the points where they are not joined.

The pad 10 in operation, as shown in Figures 3 and 4, is positioned between a wooden railroad tie 16 and a metal tie plate 17 on which a rail 18 is anchored by means of spikes, 19. Additional spikes 20 are illustrated as mounting the tie plate on the tie 16. The tie plate 17 has the conventional four spike holes 21 for anchoring the rail to the tie plate and the tie plate to the tie but since it is conventional to only use two diagonally opposite sets of holes, only two spikes 19 have been illustrated and the other pair of holes are unused. Likewise, the tie plate has the conventional four holes 22 for anchoring of the tie plate to the tie in locations of heavy traffic, curves, and the like track arrangements. Since it is conventional to use not more than two spikes at this area only two of the holes are shown as receiving spikes 20.

The pad is positioned so that the apertured spots 15 register with the diagonal opposite holes 21 receiving the spikes 19 and so that the solid spots 14 register with the diagonal opposite holes 22 receiving the spikes 20. It should be understood that spikes 19 will always be used in the indicated positions but that the spikes 20 are only used in heavy duty track locations. Therefore, the spots 15 are apertured for receiving the spikes 19 therethrough while the spots 14 are not apertured and the spikes must puncture the spots if used. The reason for not aperturing the spots 14 is to protect the railroad tie in the event that the spikes are not used as best shown in Figure 5 wherein the spots 14 covers the tie 16 across the unused spike hole 22. It will be appreciated that if the spots 14 are punctured by spikes 20, the fluid 13 will not leak out of the pad because the spot is larger than the hole 22 and the spike will only pierce the central portion of the sealed area of the spot.

As shown in Figure 4 the pad when squeezed between the tie plate and tie will follow all of the contours of the plate and tie surfaces with the fluid 13 flowing to all recesses for filling these recesses. The top face of the tie 16 is usually scarfed at 16a to receive the plate 17 and the scarfing tool frequently leaves uneven surfaces such as those illustrated at 23. As shown, the recesses under the plate 17 provided by these uneven surfaces 23 will be filled by fluid flowing into the recesses and causing the pad to bulge at these points.

As also shown in Figure 4 the tie has a bored spike hole 24 aligned with one of the unused holes 21 in the plate 17. Fluid will also flow in the pad to form a bead or bubble 25 sealing the holes 21 and 24. A similar bead or bubble 26 is formed in the unused spike hole 22.

Excess fluid in the pad 10 will be squeezed to the marginal periphery of the pad to form a raised bead 27 around the entire periphery of the plate 17. This bead 27 tightly seals the peripheral edge of the plate and the margin of the scarf area 16a of the tie 16 so that dirt cannot enter under the plate.

If spikes are placed in the unused holes 21 and 22 of the plate to puncture unsealed portions of the pad, the bubble or bead such as 25 and 26 will be broken and fluid will flow therefrom to coat the surrounding areas. However, the peripheral seals 27 and the filled voids 23 will not be disturbed because the fluid will be trapped therein by the collapse of the pad between the mating faces of the plate and the tie. Puncture of the pad at these points is, therefore, not deleterious.

In the embodiment shown in Figure 6, the pad 10a is formed from the same tube 11 as the pad 10 of Figure 1 and the end seals 12 close the end of this tube in the same manner as Figure 1. However, the pad 10a is equipped with additional spots to register with all of the holes in

a tie plate. Thus, in addition to the apertured spots 15 and the non-apertured spots 14, the pad 10a has another pair of spots 28 to register with the spike holes 21 that were unused with the pad 10 and a second set of spots 29 to register with the unused spike holes 22 in the plate shown in Figure 3.

From the above description it will, therefore, be understood that this invention provides a railroad tie hollow pad containing a liquid which remains flowable at all temperatures to which the pad will be subjected in operation. The pad is sealed but is readily deformable in full conformity with opposing tie and tie plate surfaces. When the pad is squeezed the liquid will flow to the low pressure areas. The hollow pad is of larger dimensions than the tie plate to be used in connection therewith and in flowing to the low pressure areas the liquid will, therefore, form a bead around the periphery of the tie plate in sealing relation with both the periphery and the tie. This seal will prevent ingress of extraneous material under the tie plate and will protect the tie from the elements and from any grinding action caused by grit particles between the tie plate and the tie. The hollow pad of this invention will preferably be equipped with sealed-off spot-like areas in registration with the holes in the tie plate to receive the anchoring spikes therethrough but such sealed areas need only be provided in registration with spike holes that are always used in anchoring the rail and the tie plate to the tie.

I claim as my invention:

30 1. A sealing pad adapted for protecting railroad tie plates which comprises a hollow flat pad of deformable heat-sealing plastic material, a liquid in said pad having such qualities as to be viscous under all conditions expected to be encountered, and said pad having heat-sealed spots at predetermined areas thereof sealing off said liquid from said areas.

2. A railroad tie plate sealing pad comprising a hollow flat rectangular capsule of tough polyethylene, a flowable chemically inert tar-like liquid sealed in said capsule, and seals joining opposite faces of the capsule at predetermined areas to align with holes in a tie plate for presenting flat liquid free spots to said holes, and at least some of said spots being perforated.

3. A sealing pad for a tie plate which comprises a deformable liquid-containing sealed envelope, said envelope being double walled and having oppositely disposed portions of each wall connected to form liquid-free areas, and said liquid-free areas on said envelope positioned for alignment with spike holes in the tie plate to be sealed by the pad.

4. In a rail, tie plate, spike and tie assembly of a railroad track, the improvement of a tough, flexible, hollow plastic rectangular pad between the tie plate and tie, a flowable viscous liquid in said pad, said pad having a closed marginal portion projecting beyond the periphery of the tie plate, said liquid deforming said marginal portion into tight sealing engagement with the periphery of the tie plate, and said pad having sealed areas free from said liquid aligned with the spike holes of the tie plate to receive the spikes therethrough without puncturing the liquid-containing section of the pad.
